CONCENTRIC RESONANT LINE AND CIRCUIT
THEREFORNils E. Lindenblad, Port Jefferson, N. Y., assignor
to Radio Corporation of America, a corpora-
tion of Delaware

Application August 25, 1938, Serial No. 226,674

16 Claims.

(Cl. 250—36)

The present invention relates to improvements in tuned circuits, particularly concentric resonant lines, and to circuits therefor.

Tuned circuits in the form of concentric resonant lines are used particularly in connection with short and ultra short wave circuits. These lines are, because of their construction, non-radiating in character, and are characterized by low loss. Such tuned circuits, it is known, may be used in any one or more of the following capacities: As the frequency determining element of an oscillator; as an output tank circuit; as a tuned interstage coupling circuit; and as a filter. For a complete description of concentric resonant lines, reference is made to United States Patent No. 2,120,518, granted June 14, 1938, to John F. Dreyer, Jr.; United States Patents Nos. 2,108,895 and 2,077,800, granted February 22, 1938, and April 20, 1937, respectively, to Fred H. Kroger; and to the article by Clarence W. Hansell entitled "Resonant lines for frequency control," published August, 1935, in "Electrical Engineering," pages 852 to 856.

One of the objects of the present invention is to enable a multiplicity of voltage connections to be made to a resonant line without disturbing its balance or introducing multiple degrees of freedom.

Another object is to provide an improved concentric resonant line and vacuum tube circuit which has substantially one degree of freedom.

A further object is to provide an improved oscillation generator circuit having a concentric resonant line as a frequency controlling element therefor, wherein there is reduced the possible number of modes of oscillation (i. e., degrees of freedom).

Briefly stated, the improved concentric resonant line of my invention comprises an inner and an outer concentric conductor suitably coupled together to provide a tuned circuit in generally known manner, with the addition of a plurality of separated metallic condenser plates sandwiched between the inner conductor and the outer conductor to provide condenser layers of different capacity. These condenser plates may have the form of discs located in the general line of extension of the inner conductor and whose planes are transverse of the longitudinal axis of the inner conductor, or they may be parallel to the longitudinal axis of the inner conductor.

One advantage of the improved concentric resonant line of the present invention is that the line can be terminated with disc or cylindrical

condensers, thus providing extremely short and low reactance connections to the vacuum tube elements associated with the line. One way of accomplishing this is to widen the discs beyond the normal width of the inner conductor and to attach the electrode terminals of the associated vacuum tubes directly to these discs.

The principles underlying the present invention are explained in more detail in the following description which is accompanied by drawings, wherein:

Figs. 1 and 2 show, in vertical cross-section, my improved concentric resonant line for use, respectively, with single ended and push-pull electron discharge device circuits;

Fig. 3 shows the improved concentric line of Fig. 1 used, by way of example only, as the frequency determining element of an associated single vacuum tube oscillator circuit;

Fig. 4 shows another type of improved concentric resonant line, in accordance with the invention, wherein the condenser plates are in the form of parallel cylinders, instead of the discs of Figs. 1, 2 and 3;

Figs. 5 and 6 illustrate my improved concentric resonant line in connection with associated push-pull electron discharge device oscillator circuits;

Figs. 7 and 8 respectively illustrate my improved concentric line used as voltage step-down and step-up interstage coupling elements; and

Fig. 9 is a perspective view of a physical embodiment of one of my improved concentric resonant lines and associated vacuum tube circuits.

Referring to Fig. 1, there is shown a concentric resonant line comprising an outer conductor 1 and an inner conductor 2 conductively connected together at one of their adjacent ends by an end plate 3. Inner conductor 2 is capacitively coupled at its other end to the outer conductor by virtue of a metallic plate 4 suitably spaced from end plate 5. In the space between plates 4 and 5 there are interposed separated metallic discs or plates 6 and 7, suitably mounted on insulating supports, not shown. It will thus be appreciated that the capacity between plates 4 and 5 is divided up into several series capacities by means of discs 6 and 7 sandwiched between 4 and 5.

The voltage distribution of the resonant line 1, 2 is indicated by the dotted line V, and from an inspection thereof it will be seen that the placing of discs 6 and 7 in the location shown will enable making connections thereto without introducing multiple degrees of freedom, i. e.,

modes of oscillation. The reason for this is that the vacuum tube elements themselves are capacitive and that the connection between them and the condenser plates can be made extra short and therefore of negligible inductance. The 5 thermionic electron discharge devices, together with the sandwiched capacity plates, then form a system which is essentially capacitive. The resonant line has thus only one degree of freedom.

Fig. 2 shows a concentric resonant line wherein in the inner conductor is composed of two coaxial rods 2', 2" conductively connected to opposite end plates 3 and 5 and capacitively coupled together at their adjacent ends 4', 4". Interposed between the adjacent ends 4', 4" of rods 2', 2" are metal discs 8, 9 and 10, suitably spaced apart and insulatingly mounted in a manner not shown. The voltage distribution of the concentric line of Fig. 2 is indicated by the dotted line 20 V. It should be noted that the central disc 9 is at a voltage node or zero gradient point while the discs and rods on opposite sides thereof have voltages of opposite phase.

Fig. 3 shows a concentric resonant line of the type shown in Fig. 1 connected to a vacuum tube oscillator 11. The grid of the tube 11 is connected by way of example to plate 4; while the cathode of tube 11 is connected to plate 7. Output energy is obtained from plate 12. A positive polarizing potential for the anode of the oscillator 11 is derived from source +Ep, and suitable bias for the grid is obtained by virtue of the connection consisting of choke 13 and resistance 14 placed between grid and cathode. The cathode is connected to ground through a choke 15, and the anode connected to ground by means of the blocking and by-pass condenser 16.

The system of Fig. 3 can be likened to the well known Hartley circuit, wherein a tuned circuit, in this case the concentric line, is connected between the grid and anode of a vacuum tube whose cathode is connected to an intermediate point on the inductance of the tuned circuit. The anode end of the tuned circuit is here grounded for radio frequency energy.

Fig. 4 shows how metallic cylinders arranged in parallel can be employed instead of discs to obtain my improved concentric resonant line. The resonant line consists of an outer conductor 1 and an inner conductor 17. One end of the inner conductor 17 is shown enlarged at 18 to increase the capacity existing between the conductors of the line. A multiplicity of cylinders 19, 20 and 21 placed between the enlarged end 18 and the side walls of the outer conductor serve to subdivide the capacity therebetween into series condensers, in a manner similar to the arrangements of Figs. 1 and 2. A pair of electron discharge device oscillators 22 and 23 are shown connected in parallel relation to the concentric line, whereby said line functions to stabilize or control the frequency of oscillations produced by both vacuum tubes.

Fig. 5 shows how a concentric line of the general type of Fig. 2 can be used in connection with a push-pull circuit. The resonant line is here composed of an outer conductor 24 and an inner conductor comprising a pair of separated coaxial rods 25, 25 capacitively coupled together at their adjacent ends by means of plates 26, 27. Interposed between plates 26 and 27 are a pair of separated and relatively wide condenser discs or plates 28 and 29. Discs or plates 28 and 29 are wider than plates 26 and 27 to provide a short and

low reactance connection between the same and the associated vacuum tube electrodes. The outer conductor 24 is enlarged at its center portion to accommodate the wide plates 28, 29 for complete shielding same.

The dotted line passing between the plates 28, 29 indicates a space of zero voltage relative to the metallic plates on both sides thereof. This dotted line is marked zero (0). Plates 21 and 29 are marked minus (-) while plates 26 and 28 are marked positive (+) to indicate the instantaneous relative polarities thereon at a given moment. During another portion of the cycle, the polarities on these plates will, of course, be reversed.

The circuit of Fig. 5 shows a master oscillator comprising a pair of vacuum tubes 30, 31 connected in push-pull relation to the tuned concentric line 24, 25, the latter of course controlling the frequency of operation of the oscillator tubes. The grids of tubes 30 and 31 are connected conductively to plates 28 and 29 to provide voltages of opposite instantaneous relative phase on the two grids. Similarly, the anodes of the tubes 30 and 31 are capacitively coupled to plates 21 and 26 by virtue of small plates 32 and 33 suitably spaced from plates 21 and 26, respectively. These small plates 32 and 33, as well as condenser discs 29 and 28, are insulatingly mounted in the interior of the concentric line in suitable manner, not shown. Connections 34 and 35 supply positive polarizing potentials to the anodes of the oscillator tubes from the positive terminal of a source +Ep.

The master oscillator is arranged to drive a neutralized push-pull radio frequency amplifier comprising a pair of vacuum tubes 36, 37, whose anode and grid electrodes are capacitively interconnected in known bridge fashion for neutralization purposes. The grids of the amplifier tubes are capacitively connected to plates 28 and 29, by virtue of connections 38 and 39, in turn connected, respectively, to small capacity plates 40 and 41. These last connections insure the application of opposite relative polarities at all times to the grids of the tubes 36, 37. Suitable negative bias potentials, indicated by the minus (-) sign, are applied to the grids of the amplifier tubes, while a positive (+) polarizing potential applied to the midpoint of the output tuned circuit 42 insures the application of a suitable voltage to the anodes of the amplifier tubes.

Due to the fact that plates 28 and 29 are wider than normal, the oscillator and amplifier tubes can be mounted on the enlarged central portion of the outer conductor, or if desired, directly on the plates 28, 29 to insure minimum lengths of leads between tubes and plates, and thus obtain short and low reactance connections. It is also possible to directly attach the tube electrodes to the capacity plates.

Fig. 6 shows how my improved concentric line, of a type similar to that shown in Fig. 5, can be incorporated in a unit providing either amplitude or frequency modulated output. In this figure, a master oscillator comprising a pair of push-pull vacuum tubes 43, 44 drives a radio frequency push-pull neutralized amplifier comprising a pair of vacuum tubes 45, 46. Output energy from the amplifier is derived from tuned circuit 47. For modulating the output there is provided a pair of modulating tubes 48, 49. By throwing the switch 50 to the left, the output energy can be amplitude modulated, while fre-

quency modulation can be obtained by throwing this switch to the right. When amplitude modulation is desired, only the oscillator and the radio frequency amplifier are energized. The radio frequency amplifier is then modulated. When frequency modulation is desired, the feed-back or frequency modulator is also energized. The modulator is then connected to modulate the feed-back of the frequency "modulator." The radio frequency amplifier is then not modulated but operates as a straight amplifier.

Fig. 7 indicates how the improved concentric resonant line of the type generally shown in Fig. 2 can be used as an interstage coupling element to step down the voltage between the output of radio frequency amplifier stage 51 and the input of radio frequency stage 52, each stage comprising a pair of push-pull connected electron discharge devices.

Fig. 8 shows an arrangement similar to that of Fig. 7, except that the concentric resonant line is now used to step up the voltage between the output of radio frequency stage 51 and the input of radio frequency stage 52.

The ratio of step down or step up transformation is of course determined by the power consumption in the following stage.

Fig. 9 illustrates, in perspective, a rear view of a pair of vacuum tubes 53, 54 mounted on the outer conductor of my improved concentric line for minimizing lead connections between tube electrodes and condenser plates 8, 9. The interposed or sandwiched plates 8, 9 are shown mounted on insulating supports 55. It will be evident, of course, that the metallic covers for the unit have not been shown in order to expose the interior.

Although the improved concentric line of the invention has been shown employing discs and cylinders, it will be understood that these elements may take different forms and be located at different places between the inner and outer conductors, and that various modifications may be made both in the line and associated circuit arrangements without departing from the spirit and scope of the invention. For example, the condenser plates, as well as the plates capacitively coupled thereto, can be adjustably mounted to vary the spacing therebetween and between same and the inner conductor.

What is claimed is:

1. A tuned high frequency circuit comprising concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the adjacent ends of said rods with their planes transverse to the longitudinal axis of said rods, said plates being insulated from each other and from inner and outer conductors, whereby they provide terminal connections for an associated circuit.

2. A tuned high frequency circuit comprising concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the adjacent ends of said rods with their planes transverse to the longitudinal axis of said rods,

said plates being insulated from each other and from inner and outer conductors, whereby they provide terminal connections for an associated circuit, a pair of said plates being on opposite sides of and substantially equally distant from a voltage nodal point on the voltage distribution curve of said tuned circuit.

3. A tuned high frequency circuit comprising concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the adjacent ends of said rods with their planes transverse to the longitudinal axis of said rods, said plates being insulated from each other and from inner and outer conductors, whereby they provide terminal connections for an associated circuit, at least two of said conducting plates being wider than the normal width of said outer conductor.

4. A tuned high frequency circuit comprising concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the adjacent ends of said rods with their planes transverse to the longitudinal axis of said rods, said plates being insulated from each other and from inner and outer conductors, whereby they provide terminal connections for an associated circuit, a pair of said plates being on opposite sides of and substantially equally distant from a voltage nodal point on the voltage distribution curve of said tuned circuit, said pair of plates being wider than the normal width of said outer conductor for minimizing lead lengths extending therefrom to said associated circuit.

5. A high frequency tuned oscillatory circuit comprising a container in the form of a substantially continuous metallic surface, a lumped capacitor within said surface, and a pair of inductance elements in the form of linear conductors devoid of concentrated reactance directly connecting said capacitor to said surface, said lumped capacitor including three or more condenser plates insulated from each other, at least two of said plates being insulated from said inductance elements, said plates constituting terminals for said tuned circuit.

6. In a multi-stage high frequency system, a first push-pull stage comprising a pair of electron discharge devices, a second push-pull stage also comprising a pair of electron discharge devices, an interstage coupling element comprising a concentric resonant line composed of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the ends of said rods with their planes transverse to the longitudinal axis of said rods, said plates being insulated from each other and from inner and outer conductors, and connections from the output of said first stage and the input of said second stage to said parallel plates.

7. In a multi-stage high frequency system, a

first push-pull stage comprising a pair of electron discharge devices, a second push-pull stage also comprising a pair of electron discharge devices, and an interstage coupling element between the output of said first stage and the input of said second stage, said elements comprising a concentric resonant line composed of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates spaced between the ends of said rods with their planes transverse to the longitudinal axis of said rods, said plates being insulated from each other and from the inner and outer conductors, whereby they provide terminal connections for said input and output circuits, said output circuit being connected to a pair of said conducting plates equally spaced on opposite sides of the electrical center of said resonant line, said input circuit also being connected to another pair of said conducting plates equally spaced on opposite sides of the electrical center of said line, said first pair of plates being located farther away from said center than said last pair of plates, whereby said line acts as a voltage step-down coupling element.

8. In a multi-stage high frequency system, a first push-pull stage comprising a pair of electron discharge devices, a second push-pull stage also comprising a pair of electron discharge devices, and an interstage coupling element between the output of said first stage and the input of said second stage, said elements comprising a concentric resonant line composed of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates spaced between the ends of said rods with their planes transverse to the longitudinal axis of said rods, said plates being insulated from each other and from inner and outer conductors, whereby they provide terminal connections for said input and output circuits, said output circuit being connected to a pair of said conducting plates equally spaced on opposite sides of the electrical center of said resonant line, said input circuit also being connected to another pair of said conducting plates equally spaced on opposite sides of the electrical center of said line, said first pair of plates being located nearer to said center than said last pair of plates, whereby said line acts as a voltage step-up coupling element.

9. In a high frequency system, the combination with a push-pull oscillator comprising a pair of vacuum tubes exciting a push-pull radio frequency amplifier also comprising a pair of vacuum tubes, of a frequency controlling circuit in the form of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the ends of said rods with their planes transverse to the longitudinal axis of said rods, said plates being insulated from each other and from inner and outer conductors, whereby they provide terminal connections for said vacuum tubes, a pair

of said plates being on opposite sides of a voltage nodal point on said line, said pair of plates being wider than the normal width of said outer conductor, connections from the grid electrodes of said oscillator tubes to said pair of plates, and connections from the grid electrodes of said amplifier tubes to said pair of plates.

10. In a high frequency system, the combination with a push-pull oscillator comprising a pair of vacuum tubes exciting a push-pull radio frequency amplifier also comprising a pair of vacuum tubes, of a frequency controlling circuit in the form of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the ends of said rods with their planes transverse to the longitudinal axis of said rods, said plates being insulated from each other and from the inner and outer conductors, whereby they provide terminal connections for said vacuum tubes, a pair of said plates being on opposite sides of a voltage nodal point on said line, connections from the grid electrodes of said oscillator tubes to said pair of plates, and connections from the grid electrodes of said amplifier tubes to said pair of plates.

11. In a high frequency system, the combination with a push-pull oscillator comprising a pair of vacuum tubes exciting a push-pull radio frequency amplifier also comprising a pair of tubes, of a frequency controlling circuit in the form of concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the ends of said rods with their planes transverse to the longitudinal axis of said rods, said plates being insulated from each other and from inner and outer conductors, whereby they provide terminal connections for said vacuum tubes, a pair of said plates being on opposite sides of a voltage nodal point on said line, connections from the grid electrodes of said oscillator tubes to said pair of plates, and connections from the grid electrodes of said amplifier tubes to said pair of plates, and means connected to said pair of spaced rods for modulating the energy available in said radio frequency amplifier.

12. A high frequency tuned oscillatory circuit comprising a container in the form of a substantially continuous metallic surface, a lumped capacitor within said surface, and a pair of inductance elements directly connecting said capacitor to said surface, said lumped capacitor including three or more condenser plates insulated from each other, at least two of said plates being insulated from said inductance elements, said plates constituting terminals for said tuned circuit.

13. In a high frequency system, the combination with a push-pull oscillator comprising a pair of vacuum tubes exciting a push-pull radio frequency amplifier also comprising a pair of vacuum tubes, of a frequency controlling circuit in the form of concentric inner and outer conductors, said inner conductor comprising a pair of spaced rods arranged in the same straight line and having remote ends connected to said outer conductor, the adjacent ends of said rods being so

spaced and provided with plates as to form a capacitor, and a plurality of parallel conducting plates placed between the ends of said rods with their planes transverse to the longitudinal axis of said rods, said intermediate plates being insulated from each other and from the inner and outer conductors, a pair of said intermediate plates being on opposite sides of a voltage nodal point on said line, connections from the input electrodes of said radio frequency amplifier to 10 said pair of plates, and connections from the output electrodes of said oscillator to certain of said other plates.

14. In a high frequency system, the combination with a first push-pull driving stage comprising a pair of vacuum tubes, and a second push-pull driven stage also comprising a pair of vacuum tubes, of an interstage coupling element between the output of said first stage and the input of said second stage, said element comprising 20 a concentric resonant line composed of concentric inner and outer conductors, said inner conductor comprising a pair of spaced rods arranged in the same straight line and having remote ends connected to said outer conductor, the adjacent ends 25 of said rods being so spaced as to provide a capacitor, and a plurality of parallel conducting plates placed between the adjacent ends of said rods with their planes transverse to the longitudinal axis of said rods, said plates being insulated from each other, connections from the output electrodes of said first stage to a pair of said plates which are substantially symmetrically positioned with respect to a voltage nodal point on said interstage coupling element, and connections from 30 the input electrodes of said second stage to other plates which are also substantially symmetrically positioned with respect to said same voltage nodal point.

15. The combination with a tuned high fre- 40

5 quency circuit comprising concentric inner and outer conductors, said inner conductor comprising a pair of spaced rods arranged in the same straight line and having remote ends connected to said outer conductor, the adjacent ends of said rods being so spaced as to provide a capacitor, and a plurality of parallel conducting plates placed between the adjacent ends of said rods with their planes transverse to the longitudinal axis of said rods, said plates being insulated from each other and from inner and outer conductors, whereby they provide terminal connections for an associated circuit, of a pair of vacuum tubes coupled in push-pull relation and having a pair of connections extending from corresponding electrodes of said vacuum tubes to a pair of said plates.

16. In a high frequency system, the combination with a push-pull driving stage exciting a push-pull driven stage, of a tuned high frequency circuit comprising concentric inner and outer conductors, said inner conductor comprising a pair of spaced rods arranged in the same straight line and having remote ends connected to said outer conductor, the adjacent ends of said rods being so spaced and provided with plates as to form a capacitor, and a plurality of parallel conducting plates placed between the adjacent ends of said rods with their planes transverse to the longitudinal axis of said rods, said plurality of parallel plates being insulated from each other and from said inner and outer concentric conductors, a pair of said plurality of parallel plates being on opposite sides of a voltage nodal point on said tuned circuit, connections from the input electrodes of said driven stage to said last pair of plates, and connections from the output electrodes of said driving stage to certain other plates of said plurality.

NILS E. LINDENBLAD.
